(57) **CLAIM**

The ornamental design for bullet, as shown and described.

DESCRIPTION

FIG. 1 is a top perspective view of bullet showing our new design.

FIG. 2 is a right elevational view thereof.

FIG. 3 is a front elevational view thereof.

FIG. 4 is a left elevational view thereof.

FIG. 5 is a top plan view thereof.

FIG. 6 is a rear elevational view thereof.

FIG. 7 is a bottom plan view thereof.

FIG. 8 is a top perspective view of an embodiment of the bullet with indented band as unclaimed background detail.

FIG. 9 is a right elevational view thereof.

FIG. 10 is a front elevational view thereof.

FIG. 11 is a left elevational view thereof.

FIG. 12 is a top plan view thereof.

FIG. 13 is a rear elevational view thereof.

FIG. 14 is a bottom plan view thereof.

FIG. 15 is a top perspective view of an embodiment of the bullet with indented band.

FIG. 16 is a right elevational view thereof.

FIG. 17 is a front elevational view thereof.

FIG. 18 is a left elevational view thereof.

FIG. 19 is a top plan view thereof.

FIG. 20 is a rear elevational view thereof; and,

FIG. 21 is a bottom plan view thereof.

The broken line showing of aspects of the bullet is included for purpose of illustrating environment and forms no part of the claimed design.
